UNITED STATES PATENT OFFICE.

JOHN C. ADKINS, OF STOCKTON, CALIFORNIA.

EXPANSIVE REAMER.

SPECIFICATION forming part of Letters Patent No. 788,620, dated May 2, 1905.

Application filed October 24, 1904. Serial No. 229,675.

To all whom it may concern:

Be it known that I, JOHN C. ADKINS, a citizen of the United States, residing at Stockton, in the county of San Joaquin, State of California, have invented certain new and useful Improvements in Expansive Reamers; and I do declare the following to be a full, clear, and exact description of the invention, such as will enable others skilled in the art to which it applies to make and use the same, reference being had to the accompanying drawings, and to the numerals of reference marked thereon, which form a part of this specification.

My invention relates to improvements in apparatus for boring wells, and particularly to that class designated as "reamers;" and it consists in the effective construction herein-after set forth.

My object is to produce an expansive reamer which will sufficiently ream and clear the hole, so that the casing may be easily inserted without a waste of energy or without reduction in size. This object I accomplish by the peculiar construction and adaptation of parts fully set forth in this specification and particularly pointed out in the claims appended.

In order that my invention may be readily understood and easily carried into effect, I will proceed, aided by the accompanying drawings, to fully describe the same.

Referring to the drawings, Figure 1 is a longitudinal view of my improved reamer. Fig. 2 is a vertical section of the same.

Similar numerals of reference indicate corresponding parts in both views.

1 designates the casing of my improved reamer.

1^a is an ordinary bail riveted to the casing 1. 1^b is a cable or chain attached to the same.

2 represents steel springs riveted to the casing 1 near the bottom thereof and extending downwardly therefrom, on the bottom of which springs are secured curved chisels 3.

4 represents small steel blocks cut integral to the springs 2 near the bottom thereof, said blocks being wider at the bottom than at the top.

5 represents small inwardly-extending lugs on the bottom of the blocks 4.

6 is a steel key located between the springs 2. 50

7 is an iron pin fastened into the head of the key 6.

8 is a piece of cast-iron exactly fitted into the casing 1 and surrounding the pin 7.

9 is a cap secured onto the top of the pin 7 55 and adapted to prevent the part 8 from slipping off the pin 7.

10 represents eyebolts suitably fastened to the top of the part 8. 11 represents cables or chains attached thereto. 60

12 is a chain fastened into the bottom of the key 6, on the bottom of which hangs a bell 13.

14 represents chains fastened into the bell 13 and one to each of the chisels 3.

On the outside of the casing 1 near the top 65 thereof are riveted springs 15, and 16 represents small slots in the bottom of said springs.

17 represents small pins or screws inserted through the slots 16 and fastened in the casing 1. 70

The operation is as follows: The cables or chains 11 are held taut while the reamer follows the casing of the well down until it strikes the bottom. Then the said cables or chains 11 are loosened and the jar of the 75 reamer striking the bottom causes the iron 8 to slip downward with great force. This drives the key 6 downward between the blocks 4, and this throws the springs 2 outward and the chisels 3 then ream the hole to a greater 80 width than the width of the casing of the well and thus permit said casing to slip easily downward without reduction. When the reamer comes to a stop, the part 8 is pulled upwardly by means of the cable 11 and pulls 85 the key 6 back into its position, and this by means of the chains 12 and 14 pulls the said springs 2 back into position. The whole reamer is then pulled upward by means of the said cable or chain 1^b, and the reamer is 90 ready for another drive.

Although I have shown a certain kind of mechanism for spreading the spring chisel mechanism, still any which is adapted may be used. 95

The lugs 5 act as stops for the key 6.

The springs 15 serve to hold the casing 1 tightly in the casing of the well and prevent

it from swinging, and thus entangling the chains or cables. The pins 17, working in the slots 16, are for the purpose of allowing the said springs 15 to adapt themselves to the 5 size of the casing of the well.

I have entered into a detailed description of the construction and relative arrangement of parts embraced in the present and preferred embodiment of my invention. I do not desire, however, to be understood as confining myself to such specific detail, as such changes and modifications may be made in practice as fairly fall within the scope of my claims.

Having thus described my invention, what 15 I claim as new and useful, and desire to protect by Letters Patent, is—

1. In an apparatus of the kind described the combination of a suitable casing provided with a plurality of steel springs riveted to the 20 outside of said casing near the bottom thereof and extending downwardly therefrom, suitable chisels fastened to the lower ends of said springs, steel blocks cast integral with the inside of said springs near the bottom thereof, inwardly-projecting lugs on the lower ends of said blocks, a suitable driving-key fitted between said springs, a pin fastened into the top 25 of said key, a piece of cast-iron surrounding said pin, a cap on the top of said pin, a chain secured to the bottom of said key, a bell on the lower end of said chain, chains connecting the said bell to each of said chisels, means 30 for raising said casing and means for raising said key, pin, and iron, bow-springs secured on the said casing near the top thereof, vertical slots in the lower end of said bow-springs and pins inserted in said slots and secured in 35 said casing, as set forth.
- 25 Inwardly-projecting lugs on the lower ends of said blocks, a suitable driving-key fitted between said springs, a pin fastened into the top of said key, a piece of cast-iron surrounding said pin, a cap on the top of said pin, a chain, secured in the bottom of said key, a bell on the lower end of said chain, chains connecting said bell to each of said chisels, means for

raising said casing and means for raising said key, pin, and iron, all as set forth.

2. In an apparatus of the kind described the 35 combination of a suitable casing provided with a plurality of steel springs riveted to the outside of said casing near the bottom thereof and extending downwardly therefrom, suitable chisels fastened to the lower ends of said 40 springs, steel blocks cast integral with the inside of said springs near the bottom thereof, inwardly-projecting lugs on the lower ends of said blocks, a suitable driving-key fitted between said springs, a pin fastened into the top 45 of said key, a piece of cast-iron surrounding said pin, a cap on the top of said pin, a chain secured to the bottom of said key, a bell on the lower end of said chain, chains connecting the said bell to each of said chisels, means 50 for raising said casing and means for raising said key, pin, and iron, bow-springs secured on the said casing near the top thereof, vertical slots in the lower end of said bow-springs and pins inserted in said slots and secured in 55 said casing, as set forth.

In testimony whereof I have signed my name to this specification in the presence of two subscribing witnesses.

JOHN C. ADKINS.
